WASHFOUNTAIN SPRAY HEAD

Howard G. Mullett, Whitefish Bay, Wis., assignor to Bradley Washfountain Co., Milwaukee, Wis., a corporation of Wisconsin

Application June 18, 1953, Serial No. 362,491

3 Claims. (Cl. 299—141)

The invention relates to wash fountains and more particularly to a spray head for wash fountains of the type shown, for example, in U. S. Patents No. 2,378,424, of June 19, 1945, No. 2,398,149, of Apr. 9, 1946, and No. 2,498,699, of Feb. 28, 1950.

The main object of the invention is to provide a spray head of more economical construction than those heretofore used and one of universal application in that the same spray head structure can be used whether the water supply comes from below or above the wash basin into which the spray head discharges. More particularly, instead of a large brass casting forming one of the parts of the usual spray head in which the manifold is integral with a spraying part, the manifold is now made as a reversible single smaller casting and the spray head parts are formed of stainless steel stampings clamped to the manifold in either of its positions, the stampings being cheaper than the brass parts previously used and better than the plated brass surfaces of the parts previously used.

The invention further consists in the several features hereinafter set forth and more particularly defined by claims at the conclusion hereof.

In the drawings:

Fig. 1 is a vertical sectional view through a wash fountain equipped with a spray head embodying the invention;

Fig. 2 is a vertical sectional view of a spray head as arranged to receive water from a point below the wash basin;

Fig. 3 is a view similar to Fig. 2 showing the spray head as arranged to receive water from a point above the spray head;

Fig. 4 is a top view of the manifold as arranged in Fig. 3.

Referring to Figs. 2 to 4, the spray head embodying the invention comprises a manifold 5 and spray nozzle parts 6 and 7. The manifold 5 is a generally cylindrical member having annular grooves 8 and 9 adjacent its ends and associated grooves 10 and 11. The external grooves 8 and 9 are of the same inner diameter, and the internal grooves 10 and 11 have the same outer diameter. The manifold is usually formed as a brass casting and is of generally ring shape or annular form with an inwardly projecting boss 12 apertured at one side at 13 to provide a tapered opening for a water supply pipe 15.

The nozzle member 6 is an annular plate stamping of stainless steel having a depending flange portion 16 whose edge 17 may be bevelled. This stamping has radially disposed circumferentially spaced tubular internally threaded bosses 18 welded thereto. The nozzle member 17 is also an annular plate stamping of stainless steel having a flange 19 with an upper bevelled edge 20 that fits the bevelled edge 17 of the nozzle member 6. Either one or both of these nozzle members where they abut each other at their bevelled edges 17 and 20 may be provided with grooves 21 forming spray openings. These grooves are circumferentially spaced from each other, and for a full circle wash fountain the grooves are ar-

2

ranged throughout the entire area of the nozzle, whereas for a semi-circular wash fountain such as shown in Figs. 7 and 8 of Patent No. 2,378,424, previously referred to, the spray openings are formed only in the front half portion of the spray head.

The nozzle members 6 and 7 are clamped to each other in spray forming position and to the manifold 5 by stud bolts including studs 22 anchored in the threaded bosses 18 and nuts 23 mounted on these studs and bearing 10 against fiber washers 24 which abut recessed portions 25 of the nozzle member 7 to secure a fluid-tight connection between the nozzle members 6 and 7 and the manifold 5, packing rings 26 of rubber or other suitable yielding water proof material are mounted in the recesses 8 and 9 of the manifold and engage the inner peripheral portions 15 of the spray members 6 and 7.

The opening 13 for the pipe 15 opens into the space between the nozzle members 6 and 7, and in Fig. 1 I have shown the spray head as arranged in Fig. 2 mounted 20 above a wash basin 27 as in the prior patents, this mounting is formed by a tubular support 28 which sets in its upper end in the recess or groove 10 of the manifold 5, the spray head being clamped in position upon the upper end of the pipe or support 28 by a headed tie bar 29, a cross bar 30, and nut 31 engaging the lower threaded end of the tie bar 29. The tie bar 29 extends through an opening 32 in a cover plate 33. Cover plate 33 has the same outer diameter as that of the support 28, and these diameters are such as to fit either the internal groove 10 or 11.

In Fig. 3 the nozzle member is supported by the same type of tubular support 28 as previously described but is held to this support by the connection of a cover plate 33a through a set screw 34 engaging a vent pipe 35, and 35 in this form it will be noted that the manifold 5 has been turned over from the position shown in Fig. 2 so that the water supply pipe 15 comes in from the top instead of the bottom. Various types of valves some of which are shown in the prior patents above referred to may be used 40 to control the supply of water to the pipe 15.

I desire it to be understood that this invention is not to be limited to any particular form or arrangement of parts except in so far as such limitations are included in the claims.

What I claim as my invention is:

1. In a wash fountain spray head, the combination of a cast metal manifold of tubular form having an inwardly extending eccentrically disposed boss provided with a single water inlet and having concentric external centering means at its ends, a pair of stamped metal annular nozzle members having edge engaging spray forming outer peripheral flanges and having inner peripheral portions engageable with either of said centering means of said manifold, sealing means between the inner peripheries of the nozzle members and said manifold, and means for clamping said nozzle members together and to said manifold, said manifold being reversible relative to said nozzle members whereby said water inlet may be disposed at the top or bottom of said spray head.

2. In a washfountain spray head, the combination of a cast metal manifold of tubular form having an inwardly extending eccentrically disposed boss provided with a single water inlet and annular peripheral concentric recesses of the same internal diameter adjacent its ends, a pair of annular metal plate stampings forming nozzle members having edge engaging spray forming peripheral flanges and having inner peripheral portions fitting either of said peripheral recesses of said manifold, sealing rings disposed in said recess and engaged by said nozzle members, and means for clamping said nozzle members together and to said manifold, said manifold being reversible

relative to said nozzle members whereby said water inlet may be disposed at the top or bottom of said spray head.

3. In a washfountain spray head, the combination of a cast metal tubular manifold having external concentrically disposed grooves of the same internal diameter at opposite end portions thereof and internal concentric grooves of the same external diameter at opposite ends thereof, said manifold having an inwardly extending eccentrically disposed boss provided with a single water inlet, a pair of annular stainless steel plate stampings having edge engaging spray forming peripheral flanges and having inner peripheral portions of the same diameter to engage in either of said external grooves of said manifold, sealing means between the inner peripheries of said plates and said manifold, one of said plates having inwardly extending threaded bosses, bolts extending through the other of said plates and engaging in said threaded bosses to clamp said plate members together and to said manifold, sealing means interposed between the heads of

10

15

said bolts and the adjacent plate, a tubular support and a circular cover member having the same external diameter as said support, said support and cover member adapted to engage in either of said internal grooves of said manifold whereby said manifold may be reversed relative to said plates, said support and said cover member to dispose said water inlet at the top or bottom of said spray head.
